(57) **CLAIM**

The ornamental design for a wide body traction stud, as shown and described.

DESCRIPTION

FIG. 1 is a rear elevational view of a wide body traction stud for use on snowmobile drive belts and the like, showing my new design of the present invention;

FIG. 2 is a side elevational view thereof taken from the left side of FIG. 1, it being understood that the opposite side is a mirror image thereof;

FIG. 3 is a front elevational view;

FIG. 4 is a top view thereof; and,

FIG. 5 is a bottom view of FIG. 3.
